UNITED STATES PATENT OFFICE.

HELEN S. CARSON, OF CHICAGO, ILLINOIS.

BOOK-MARKER.

1,168,159.

Specification of Letters Patent. Patented Jan. 11, 1916.

Application filed May 13, 1915. Serial No. 27,829.

To all whom it may concern:

Be it known that I, HELEN S. CARSON, a citizen of the United States, and a resident of Chicago, in the county of Cook and State 5 of Illinois, have invented certain new and useful Improvements in Book-Markers, of which the following is a specification.

This invention is an improvement in book markers of that type especially designed and 10 adapted for use by followers of what is generally known as Christian Science, and is more particularly an improvement upon my Patent Number 1,056,322, granted March 18, 1913.

15 The primary object of this invention is to do away with the use of ribbons for holding the several marks in place within the book as arranged, and to utilize cover engaging strips, preferably of an adjustable nature 20 adapting them for use in connection with books of different sizes, in place of such ribbons as illustrated in my patent above referred to.

A further object is to provide a marker, 25 the main arm of which is in the form of a separate piece connected to the marker in a rigid and convenient manner.

Still another object of my invention is to provide a second and adjustable sub-arm for 30 each of the markers, in addition to its main arm and the sub-indicator.

These objects, and the advantages resulting therefrom, will be readily apparent from the following description in which reference 35 is made to the accompanying drawings, forming a part of this specification, and in which—

Figure 1 is a perspective view of a book partly open and provided with my improvement. Fig. 2 is a similar view of a portion 40 of the book, closed, and looking from the outside. Fig. 3 is a plan view of the rear portion of the book, partly broken away and in section. Fig. 4 is an elevation of one of the markers, illustrating its main and sub-indicating arms. Fig. 5 is a plan view of 45 one end of the blank of one of the cover engaging strips. Fig. 6 is a similar view of one of the connecting strips. Fig. 7 is a plan view of the adjacent adjustably connected 50 ends of two sections of one of the cover engaging strips, illustrating a portion of the connecting strip shown in Fig. 6, in operative relation therewith. Fig. 8 is a detail 55 section through one of the markers, taken

substantially on line 8—8 of Fig. 4. Fig. 9 is a perspective view illustrating the adjustable form of cover engaging strip, parts of which are shown in Figs. 5, 6, and 7. Fig. 10 is a perspective view of one end portion 60 of one of the cover engaging strips illustrating a slightly modified form thereof, and Fig. 11 is a plan view of one end of the blank from which the modified form shown in Fig. 10, is prepared.

65 Referring now to these figures, and as in my patent above referred to, each of the markers A comprises a body portion A' with an eye A² at one end and an extension bar A³ at its opposite end, which extension bar 70 has an eye A⁴ at its free end, the main indicating bar B in the present instance, which extends laterally from the body A of the marker, and is provided with transverse slots B' through which a main indicating 75 strip C is passed in interlocking the said indicator C with the said arm.

It is to be noted that the indicating strip C and the extension bar A³ are each interlocked with the respective parts carrying the 80 same, in the manner shown and described in my patent above referred to, and to which it is therefore unnecessary to repeat at present. Attention is, however, called to the fact that in the present instance the main indicating arm B has laterally extending lugs B² at its inner end which are bent and clamped through small recesses formed in the body A' of the marker A to securely lock the arm B in place without the necessity of 85 an integral formation as shown in my patent. In the present instance, also, I preferably provide, in addition to the main indicating bar B, with its indicating strip C, and the sub-indicators as shown in my patent, 90 one or more adjustable sub-indicating arms D such as plainly seen in Figs. 1 and 4, each of these arms having a reduced extension D' at one end adapted for engagement through slots A⁵ arranged in pairs and extending in 95 a series along the major portion A' of the marker, it being noted that each of the arms D is also provided with an integral tongue D² for engagement upon the opposite surface of the body A' so as to effectively prevent accidental displacement of the extension D' with respect to the slots A⁵ through 100 which it has been extended to maintain the sub-indicating arm D in selected adjustment 105 with respect to the marker.

110

The main indicating bar B may, if so desired, be secured by connecting means similar to those just described for securing the sub-indicating arms D.

5 As in my patent above referred to, the several markers A are connected by laces E extending through the eyes A² and A⁴, one of the laces being disposed adjacent each end of the book. In the present case, as will 10 be particularly seen by reference to Fig. 2, two laces are employed, the lace at each end of the book being independent of the other and being extended through eyes f in tongues F' struck upwardly from the bent 15 ends F² of the cover engaging strip F as plainly seen by reference to Figs. 1 and 2, one of these strips being disposed along the inside of each cover, with its bent end F² extending outwardly over the upper and 20 lower edges of the cover, the tongues F' thus projecting upwardly substantially in a line with the ends of the markers. The bent ends F² are preferably provided with slots f' 25 which receive the spear shaped head G' of a connecting strip G extending across the covered edge of the book and connecting the respective ends of the two cover engaging strips F. As also seen in Fig. 2, the laces E are preferably tied across the covered edge 30 of the book after passage through apertures f² in the bent outer ends F² of the cover engaging strips F.

As will be seen by reference to Figs. 7 and 9, each of the strips engaging the book covers and corresponding to the strips F as seen 35 in Fig. 1, is preferably formed of two sections F³ and F⁴, each of these sections having at its inner end pairs of slots f³ and f⁴, thus providing for adjustment in length of 40 the book engaging strip by connecting the sections F³ and F⁴ through the use of an adjustable connecting strip F⁵ having spear shaped engaging ends F⁶ adapted for extension through the slots f³ and f⁴ and being 45 thus practically a counterpart of the connecting strip G before mentioned and shown in detail in Fig. 6. Furthermore, as seen in Figs. 10 and 11, the upstanding tongue f⁵ of the cover engaging strip F', may be in the 50 nature of a lateral extension, see Fig. 11, which is bent upon one face of the said strip F' opposite to that upon which the extension f⁶ is bent which carries the slots for the connecting strip G and the aperture for the lace. 55 It is obvious, therefore, that the present means of securing the laces E and maintaining the series of markers against relative displacement after proper adjustment, are much improved in doing away with the use 60 of crossed ribbons extending exteriorly of the book for supporting the laces E as in my patent above referred to, and substituting therefor cover engaging strips, the bent ends of which, with the connecting strips G 65 and portions of the markers and laces E are

alone exposed to view upon the exterior of the book, and the sections of which by their adjustable connection through the connecting strip F⁵, provide for the attachment and operation of the cover engaging strip with 70 books of different sizes.

I claim:—

1. A book marker having a pair of transverse slots therein, and a main indicating bar having extensions clamped through said 75 slots to rigidly hold the bar in position.

2. A book marker having a series of slots arranged in transverse pairs and provided with a rigid main indicating bar, and a sub-indicating bar adjustable on the marker and 80 having an extension at one end for engagement in selected pairs of said slots, and having also an integral struck up tongue for engagement with the marker in adjusted position, whereby to prevent displacement 85 thereof.

3. A book marker having a longitudinal series of slots and a rigid main indicating bar, and a sub-indicating bar provided with means engageable in selected slots of the 90 marker, and other means engageable with the marker to lock said sub-indicating bar in adjusted position.

4. A book marker having an eye, a lace extending through the eye, and securing 95 strips with which said lace is connected, said strips extending along the inner surfaces of the sides of the book cover and having means to engage the said cover sides.

5. A book marker having an eye, a lace 100 extending through the eye, and cover engaging strips extending along the inside of the cover sides of the book and having exteriorly bent ends provided with eyes 105 through which the lace also passes.

6. A book marker having eyes, laces extending through the eyes, and securing means for the said laces consisting of cover engaging members to which the laces are connected extending along the inside of the 110 cover sides, said members being adjustable in length and having bent ends engaging the upper and lower edges of the said cover sides.

7. A book marker having eyes, laces extending through the said eyes, and securing 115 means for the laces consisting of strips extending along the inner sides of the book covers and having their ends bent over upon the exterior of the book covers and provided 120 with upstanding eyes through which the laces may be connected.

8. A book marker having eyes, laces extending through the eyes, and securing means for the laces consisting of strips adjustable in length and extending along the inner portions of the book covers, and provided with upstanding eyes through which the laces may be connected, and connecting strips extending across the back of the book 130

and detachably engaging the relatively opposite bent ends of the said strips.

9. A bookmarker having a pair of slots, and an indicating bar carried by the said marker and having means at one end engageable through the said slots, and also having an integral struck up tongue adjacent said end for engagement with the body of the marker to prevent displacement of 10 said engaging means from the said slots.

10. A device of the character described including a plurality of book markers, flexi-

ble connecting members supporting the said markers, members extending along the inside of the cover sides and having bent ends engaging the upper and lower edges of the said cover sides and to which the said flexible connecting members are joined, and connecting strips between the said bent ends and extending across the back of the book cover. 15

HELEN S. CARSON.
